UNITED STATES PATENT OFFICE.

OSKAR KYLIN, OF ELKHART, INDIANA, ASSIGNOR TO FOSTER MACHINE COMPANY,
OF ELKHART, INDIANA, A CORPORATION OF INDIANA.

CORE-MAKING MACHINE.

Application filed November 3, 1921. Serial No. 512,435.

To all whom it may concern:

Be it known that I, OSKAR KYLIN, a citizen of the United States, residing at Elkhart, in the county of Elkhart and State 5 of Indiana, have invented certain new and useful Improvements in Core-Making Machines, of which the following is a specification.

This invention relates to machines for 10 making sand cores that are to be used for molding a hollow cylindrical body. The invention has been designed more especially for producing cores of the type employed in molding the pistons of internal combustion engines, pump plungers, and other pistons of the hollow cylindrical type, which are commonly formed with internal longitudinal and radial re-enforcing ribs; but in 15 its broader aspects the invention is not limited to a machine for forming cores of this special type, but is equally adaptable for the formation of cores to be used in the subsequent molding of any generally cylindrical hollow structure.

20 My present invention, is of that type wherein the body of the core box is made up of a plurality of cooperating segments that unitedly form a generally cylindrical box, which segments may carry internal ribs, bosses, and the like, and the chief novel 25 features of the invention reside in a mechanism by which the segments may be withdrawn radially from the molded core without disturbing or injuring the latter and 30 may be subsequently moved back into operating relation to receive the sand for the next core; and novel mechanism by 35 which, after the core box is loaded and rammed it may be inverted for the subsequent 40 retraction of the segments.

Other novel structural features and advantages of the invention will be understood and appreciated by those skilled in the art as the same becomes better understood by 45 reference to the accompanying drawings wherein I have shown one approved embodiment of the invention, and in which—

Fig. 1 is a top plan view of the machine, partly broken out and in section; 50 Fig. 2 is a sectional detail taken on the line 2—2 of Fig. 1;

Fig. 3 is a vertical section taken on the line 3—3 of Fig. 1, and broken out between its upper and lower ends;

Fig. 4 is a top plan view; and

Figs. 5 and 6 are side elevations at right angles to each other of the center forming member, the upper portion of the core box body, and the means for separably locking the former to the latter;

Fig. 7 is a fragmentary side elevation showing a portion of the invertible annular body member of the machine, the lower portion or print member of the core box, and plate member for closing the print, and means for locking said plate member in place; and

Fig. 8 is a bottom plan view of Fig. 7. Referring to the drawings, 10 designates a circular table or platform, at diametrically opposite sides of which are mounted two pairs of parallel posts 11. Slidably mounted on these posts 11 are blocks 12, in each of which latter is journaled an inwardly extending horizontal forked member 13. Each of these latter is strongly attached, as by means of screws 14, to, and supports, a central annular body member structurally composed, as herein shown, of a central sleeve 15, a lower broad annular 80 flange 16, and radial ribs 17 connecting the sleeve and flange.

Disposed centrally within the sleeve 15 is the core box proper. This comprises a group of segments. As herein shown there are 85 two oppositely disposed major segments 18, and on each side of and between the latter are a pair of minor segments 19, making six in all; but, of course, the number and relative sizes of the segments are immaterial, 90 and may be varied according to the special form of core to be molded. The particular core box herein shown being designed to mold a core to be used in the subsequent manufacture of hollow pistons, the segments 18 are shown as carrying internal bosses 20, and the segments 19 as carrying internal ribs 21.

As clearly shown in Fig. 3, the outer surfaces of the segments are tapered, as shown at 22. To bond the segments together I employ a removable collar 23, the inner surface of which is correspondingly tapered in the reverse direction, as shown at 24 so as to fit snugly the assembled segments with a 100 wedging and clamping action. The collar 23 is vertically slotted at intervals as shown at 25 in Fig. 3 for a purpose hereinafter disclosed.

26 designates a disc for closing one end of 110

the core box, said disc carrying on its inner surface an annular rib 27 to form a corresponding annular groove in the core by which the central rib is subsequently molded 5 on the underside of the head of the piston. This center forming member 26 is removably locked on the core box by the means clearly shown in Figs. 4, 5 and 6, consisting of oppositely disposed upwardly extending locking plates 28 attached to an oppositely disposed pair of segments formed and with cam notches 29 in one edge thereof that are engaged by pins 30 extending from the periphery of the cap 26.

10 Referring to Figs. 7 and 8, 31 designates a plate that forms a closure for the lower end or print 32 of the core box, said plate being herein shown as of rectangular form and provided on its lower side with a central integral circular pedestal 33, adapted to rest upon the foundation plate or table 10, as clearly shown in Fig. 3. This plate is locked removably on the print by means of a pair of grippers 34 secured to the lower 15 surface of the flange 16 of the annular body member by screws 35 and springs 36. The grippers 34 have notched inner ends 37 that engage with one edge of the plate 31, and are held engaged with said plate by a pair of studs 38 set in the lower side of the flange 16 and embracing the heel of the gripper 34. The opposite edge of the plate 31 is engaged by a similar gripper 34' secured to the underside of the flange 16 by 20 bolt 35 and spring 36. The gripper 34' is formed at its inner end with a notch 37' having a rounded vertical wall, and the heel of the gripper is equipped with a handle 38 by which it may be swung into and out of engagement with the plate.

25 The radial ribs 17 of the annular body member are formed with slideways 13, as best shown in Fig. 2, on one side thereof, the lower edge of the slideway having a dove-tail formation as shown at 39', and a similar dove-tail formation being provided at the upper edge by means of a strip 40 secured to the top of the ribs 17 and equipped with an inclined lip or flange 40'. In this slide- 30 way or guide is mounted a slide bar 41, the inner end of which passes through the slot 25 of the clamp collar 23, as clearly shown in Fig. 3, and is attached to one of the segments 18, 19, as by means of a pivot screw 42. To actuate the several slide bars 41 simultaneously, I provide a group of elbow levers that are pivoted at 43 on upstanding lugs 44 (Fig. 2) on the flange 16 of the annular body member. The short arm 45 of each elbow lever enters a slot 46 in the slide bar 41, said slot preferably being formed with rounded vertical ends to provide line contact with the lever arm. The long arms 47 of the levers are forked as shown at 47' 35 and straddle pins 48 mounted in a hand ring

49 that encircles the annular body member and is itself slideably supported in and by trunnion forks 13, as clearly shown in Fig. 3, so that said hand ring can be manually turned to a limited extent in either direction independently of the annular body member.

50 The upper ends of the posts 11 are rigidly connected by a yoke bar 50, the ends of which latter are keyed to the posts by set screws 51. In each of the blocks 12 is an eye-screw 52, to which is attached a rope or cable 53 extending upwardly and over a pulley 54 mounted in brackets 55 which are in turn mounted on the yoke 50. The cables 53 preferably lead thence over flat vertical pulleys (not shown) and carry counterweights 56 designed to approximately balance the annular body member and its associated parts, so as to readily facilitate the raising of the latter.

57 Describing now the mode of manipulating the apparatus, the core box, with the bonding collar 23 thereon, the center plate 26 locked thereon, the print cover 31 removed, and in inverted position relatively to the showing in Fig. 3, is filled and the core properly rammed. The print plate 31 is then put in place by first placing one edge in engagement with the grippers 34 and then swinging the gripper 34' into locking engagement with the opposite edge. The entire structure is then moved upwardly on the posts 11, is turned one-hundred eighty degrees in the trunnion blocks 12 and is then lowered until the pedestal 33 of the print closure comes to rest on the table 10. The parts are then in the position shown in Fig. 3. The clamp collar 23 is then removed, as is also the center forming member 26.

58 The operator then grips the hand ring 49, and turns the same in the direction indicated by the arrow in Fig. 1. This through the bell cranks and slide bars effects simultaneous and equal retraction in radial directions of all of the core segments. The molded core is thus left resting on the core plate 31, and this latter with the core is removed. The core plate 31 is disengaged from the grippers 34 by pulling the latter down against the springs 36 until they clear the studs 38 and then swinging them to one side. Similarly the gripper 34' is then depressed by the handle 38 until disengaged from the core plate and then similarly swung to one side. To proceed with the formation of the next core, the core forming segments are closed by turning the ring 39 in the reverse direction, the clamp collar 23 and center plate 36 are then applied. The mechanism is then again raised sufficiently above the table 10 and again swung through the angle of one hundred eighty degrees and lowered into position, ready to receive the sand for the core.

60 The cables and pulleys are preferably employed for supporting counterweights to

render easier the described operation, particularly the raising and lowering of the mechanism to enable it to be inverted; but these parts are not essential as the device is capable of successful use without them.

In a core box of the segmental type, and especially where the segments are equipped with internal ribs or the like for molding recesses in the core, it is essential to secure perfect results that the segments be retracted in exact radial directions, and preferably simultaneously, since otherwise injury and defacement of the fragile core is likely to result.

It will be obvious from the foregoing description and illustration that my present machine is well adapted for this purpose. Manifestly, modifications and variations in detail from the apparatus shown will readily suggest themselves to those skilled in the art, and such variations and modifications may be made without involving any departure from the spirit of the invention or sacrificing any of the advantages thereof. Hence, I reserve all such changes and mechanical equivalents as fall within the spirit and purview of the appended claims.

I claim:

1. In a core machine, the combination of a plurality of core forming segments having tapered outer surfaces, an internally tapered annular member adapted to clampingly engage said tapered surfaces of said segments, radially movable segment-actuating members pivotally attached to the outer sides of said segments, relatively stationary guides forming supports for said movable members, and means for actuating said movable members.

2. In a core machine, the combination of a plurality of core forming segments having tapered outer surfaces, an internally tapered collar adapted to fit over the tapered outer surfaces of said segments and bond the latter together, radially movable slide-bars attached to said segments, relatively stationary guides formed with slideways for said slide-bars, and means for actuating said slide-bars.

3. In a core machine, the combination of a plurality of core-forming segments, a center-forming member removably attached to said segments, radially movable segment-actuating members pivotally attached to the outer sides of said segments, relatively stationary guides supporting said movable members, and means for actuating said movable members.

4. In a core machine, the combination of a plurality of core-forming segments, a center-forming member removably attached to said segments, radially movable segment-actuating members pivotally attached to the outer sides of said segments, guides for said segment-actuating members, a body member forming a support for said guides, and

means carried by said body member for actuating said segment-actuating members.

5. In a core machine, the combination of a plurality of core forming segments, a center forming member removably attached to said segments, radially movable members secured to said segments, guides for said radially movable members, a body member forming a support for said guides, a plate member removably attached to said body member, and means pivoted on said body member for actuating said radially movable members relatively to said body member.

6. In a core machine, the combination of a plurality of core forming segments, a removable clamp collar adapted to bond together said segments, a center forming member removably attached to said segments, radially movable slide-bars secured to said segments, guides for said slide-bars, a body member forming a support for said guides, and means mounted on said body member for actuating said slide-bars.

7. In a core machine, the combination of a plurality of core forming segments having tapered outer surfaces, a removable internally tapered member adapted to engage said tapered surfaces of said segments, a center forming member removably secured to said segments, radially movable members secured to said segments, guides for said radially movable members, a body member forming a support for said guides, means pivoted on said body member for actuating said radially movable members, and a core supporting member removably mounted on said body member.

8. In a core machine, the combination of a plurality of core-forming segments, a removable clamp collar adapted to bond together said segments, radially movable segment-actuating members pivotally attached to the outer sides of said segments, guides for said segment-actuating members, a body member carrying said guides, and means for simultaneously actuating all of said segment-actuating members.

9. In a core machine, the combination of a plurality of core forming segments having tapered outer surfaces, a removable internally tapered collar adapted to engage said tapered surfaces of said segments, a center forming member removably secured to said segments, radially movable slide-bars secured to said segments, guides for said slide-bars, a body member forming a support for said guides, a core supporting member removably attached to said body member, levers pivotally attached to said body member for actuating said slide-bars, and means for simultaneously actuating said levers.

10. In a core machine, the combination of a plurality of core forming segments, radially movable members secured to said segments, guides for said members, a body mem-

- ber forming a support for said guides, means pivoted on said body member for actuating said radially movable members, and an annular member operatively connected with said means for effecting the simultaneous operation of said radially movable members.
11. In a core machine, the combination of a plurality of core forming segments, radially movable slide-bars secured to said segments, guides for said slide-bars, a swiveled invertible body member forming a support for said guides, and means on said body member for effecting the simultaneous operation of said slide-bars.
12. In a core machine, the combination of a plurality of core forming segments, radially movable slide-bars secured to said segments, guides for said slide-bars, a swiveled invertible body member forming a support for said guides, means for actuating said slide-bars and segments relatively to said body member, and means for raising or low-

ering said body member preliminary to inverting the same.

13. In a core machine, the combination of a plurality of core forming segments having tapered outer surfaces, an internally tapered collar adapted to engage said tapered surfaces, a center forming member removably secured to said segments, radially removable slide-bars secured to said segments, guides for said slide-bars, a revolvably mounted body member forming a support for said guides, a core supporting member removably attached to said body member, levers pivoted on said body member for the actuation of said slide-bars, an annular member operatively connected with all of said levers for the simultaneous operation of said slide-bars, and means for raising and lowering said body member, preliminary to revolving the same.

OSKAR KYLIN.
